BASE FOR MACHINE OR OTHER LIGHT GUN

John W. Poysa, Los Angeles, Calif.

Application March 1, 1939, Serial No. 259,160

22 Claims.

(Cl. 89—37)

My invention relates to a base or mounting for ordnance, particularly of the type of a high angle firing gun, especially of an anti-aircraft gun. My invention however depending on the size and the strength may be made for a light type of gun such as a machine gun or of a heavy machine gun or where desired for a mounting for a larger gun firing a shell inserted in the breech for each shot.

One of the main objects and features of my invention is in the provision of a seat for the operator of the gun such as a machine gunner by which in all positions of a traverse of the gun in an arc of a circle or in the elevation of the gun for low or high angle firing the eyes of the machine gunner may be held substantially in alignment with the sights of the gun. Therefore as the gun is swung in a circle for traversing the field of fire, the seat together with footrests for the machine gunner may also swing in a circle and further in the elevation of the line of fire which may be considered the vertical arc, the gun may shoot from a considerable inclination below the horizontal to within a few degrees of the vertical. By an interconnected mechanism for moving the gun in its vertical arc with the support for the seat and also foot rests, the seat is raised and lowered and also tilted so that the machine gunner is in the proper position for sighting on target, the seat incidentally having an inclinable backrest so that even in high angle firing the gunner is comfortably supported.

Considered in more detail as to the vertical arc of movement of the gun and of the machine gunner's seat and footrest, these may be manipulated by the gunner himself and my invention comprehends a main or single control wheel for the vertical arc of aiming a gun. This wheel in a vertical plane operates a horizontal shaft, which shaft through the medium of a chain drive at one end and a pinion operating a rack, such pinion raises and lowers a rack bar which in its turn raises or lowers a supporting yoke for the gun. Then by means of a curved cam arm operating in relation to fixed guide pins or the like the gun is automatically tilted while its support is being raised and lowered, that is, the yoke on which the gun is mounted is given a tilt rotating on a horizontal pivot, the plane of rotation being vertical.

A characteristic of the manipulation of the seat with the tilting of the back rest involves a quadrant operated by a pinion gear from the main elevation control shaft. This quadrant rotates a rock shaft which in its turn through

the medium of a crank and link actuates a parallelogram of links and levers, this having the function of raising and lowering the machine gunner's seat, there being an extension of a quadrilateral link and lever connection which automatically tilts the back and the seat to accommodate the machine gunner in an upright position leaning slightly forward for low angle fire to a reclining position for high angle fire.

5 10 15

My invention further comprehends a link and lever connection for a foot rest actuated simultaneously with the movement of the seat so that the machine gunner may place his feet in a comfortable position for any position of his body resting on the seat and the seat back.

My invention involves and comprehends also mechanism for a quick traverse of the field of fire by rotating part of the gun mounting on a vertical axis and in having a minute adjustment 20 by means of a hand wheel and worm. The worm engages a worm wheel on a tubular support for the gun, however the operating shaft and worm wheel are pivoted in the housing so that the worm may be quickly disengaged from 25 and again engaged with the worm wheel. When disengaged the upper part of the column supporting the gun may be swung freely on a vertical axis and in a complete circle. Then by engaging the worm with the worm wheel and locking this 30 in position a slow or more or less micrometer adjustment can be obtained for a traverse of the field of fire rotating on the vertical axis and what might be considered as covering the horizontal or angle of fire in a transverse arc.

35 A further characteristic of my invention is the employment of a base mounting for a gun of the type described which may be made comparatively light for a light weight machine gun or heavy and substantial for larger guns but no 40 matter what the size the assembly may be readily connected and disconnected for transport and moving from one place to another. To obtain this result I have a foot construction which may be placed on or bolted to a suitable ground 45 structure or floor. This has a cylindrical pedestal extending upwardly and on the pedestal is mounted the hollow column having the direct support for the yoke or other carriage for the gun. The column also forms the supports for 50 the seat and the pivotal connection for the foot rest. This column also has journals for the main horizontal shaft which controls the elevation of the gun and also forms the mounting for the worm gear used to mesh with the worm on the pedestal for the traversing of the gun.

My invention also presents a characteristic of a brake which interacts between the pedestal and the column through which when the gunner is in line with a target as to his horizontal traverse he may readily lock the column to the pedestal and thus continue the aiming and firing by tilting the gun in a single vertical plane. My invention also comprehends an adjustment for the gun as to the yoke on which it is mounted. This is a manual control. At the rear end of the yoke and in a convenient position so that the machine gunner can readily loosen a friction clip on a rod sliding through a mounting of the yoke and thus after he has made his main adjustments to correct the elevation or vertical angle of fire he may make a more minute adjustment by hand manipulation and then lock the gun or the gun carriage to the yoke in the desired position. My invention also comprehends a number of detail features of the construction hereunder specified in detail.

My invention is illustrated in connection with the accompanying drawings, in which:

Fig. 1 is a side elevation taken in the direction of the arrow 1 of Fig. 2.

Fig. 2 is a front elevation taken in the direction of the arrow 2 of Fig. 1.

Fig. 3 is a vertical longitudinal section on the line 3—3 of Fig. 2 in the direction of the arrows.

Fig. 4 is a horizontal section on the line 4—4 of Fig. 3 in the direction of the arrows illustrating the disengageable worm with the worm wheel for transverse movement of the gun carriage.

Fig. 5 is a detail elevation taken in the direction of the arrow 5 of Fig. 4.

Fig. 6 is a horizontal section on the line 6—6 of Fig. 3 in the direction of the arrows illustrating the main shaft for elevation tilting of the gun and the latching equipment therefor.

Fig. 7 is a horizontal section on the line 7—7 of Fig. 3 in the direction of the arrows illustrating the brake for clamping the column and hence the gun to the pedestal.

Fig. 8 is a vertical section on the line 8—8 of Fig. 3, certain of the interior parts being shown in elevation and broken away with the lift rod shown in elevation.

Fig. 9 is a vertical section on the line 9—9 of Fig. 3 in the direction of the arrows illustrating the main horizontal rock shaft and the parts connected thereto.

In my invention I have a supporting assembly 11 which is indicated as having a conical shaped foot 12, this being curved outwardly and merging with a horizontal shoe plate 13. This latter gives considerable spread and with the foot a sufficient area to support the weight of the mounting and the gun carried thereby. This may be bolted or otherwise fastened to a foundation. The foot has an annular shoulder 14 and extending upwardly from this is a cylindrical pedestal 15, the pedestal terminating at a closed cap end 16 but having a right angular recess 17 therebelow. In this recess there is a worm wheel gear 18 shrunk into place. The cap has a central perforation 19 for a purpose hereunder described.

The main column mounted on the pedestal and designated by the assembly numeral 25 has a cylindrical inside surface 26 fitting over and forming a rotational fit on the cylindrical pedestal. This has a recess 26' at its lower portion and a lower edge 27 having a clearance above the shoulder 14. The column has a cover plate or cap 28 preferably formed integral therewith and is sup-

ported for rotation by a thrust shaft 29 seated on the cover 28 and held in place by a set screw 30 which extends through the opening 19. A thrust sleeve 31 surrounds the shaft 29 and engages the underside of the cap 28 and rests on an anti-friction thrust bearing 32, this being illustrated as having a lower race resting on the cap 16, an upper race engaging the thrust or spacing sleeve 31 with ball or suitable anti-friction bearings in-between. It will thus be seen that the column is free to rotate on the pedestal. The rotating gear drive designated by the assembly numeral 35, note particularly Figs. 3, 4 and 5, includes the following characteristics: the column at one side is provided with an outwardly extending locking plate 36 terminating in a lip 37. The other side has a pair of ears 38 and between these there is a lower horizontal extending plate 39 with a similar upper plate 40, thus forming an opening 41 extending inwardly through the column to the worm gear 18. A gear journal block 45 has an inner end block 46 mounted between the ears 38 by the pintle pin 47. The opposite or remote end 48 has a cylindrical curved face 49 conforming to the curve of the radius of the inside surface of the wall 36. A recess 50 is constructed in the block 45 and this accommodates a worm 51, this being secured to a hollow shaft 52 which is journaled in the block ends 46 and 48, such block ends being connected preferably by a web 53. A hand wheel 54 is secured to the shaft 52 and by means of this the worm 51 and the worm gear 18 may be rotated.

The locking assembly 55 for the worm and worm gear includes a locking bolt 56 mounted in the remote end of the hollow shaft 52, this shaft having a recess or enlargement 57 to accommodate the bolt. The bolt may engage in either of two bolt holes, 58 for the locked position and 59 for the open position. A stem 60 is connected to the bolt and has a finger grip head 61 thereon which is centrally located as regards the wheel 54. A compression spring 62 engages the base of the recess 57 and the bolt 56 urging this into its locking or locked position. In the illustration of Fig. 4 the bolt and hence the journal block 45 and the worm 51 are shown in locked position with the worm in driving relation with the worm wheel 18, however when it is desired to open this gear connection or drive the stem 60 is pulled outwardly by an outward pull on the head 61 thereby restricting the bolt from the bolt hole 58 swinging the journal block on its pintle 47 which brings the block to a stop at the rim 37. The release of the bolt then causes this to drive into the bolt hole 59 thereby holding the journal block and the worm 51 out of driving relation with the worm wheel 18. The worm wheel 18 as above described is stationary and the column rotates around the center of the pedestal on which the worm of the wheel is concentric.

The brake assembly designated 65, note particularly Figs. 1 and 7, has a brake band 66 encircling the lower portion of the pedestal above the shoulder 14 and fitting in the recess 26'. This band has two end pieces 67 and 68, note Fig. 7, extending through an opening in the column 25. Such column is provided with a boss 69. A thrust thimble 70 engages the end flange 67 and a second thimble 71 engages the end flange 68 of the brake band. A bolt 72 extends through these thimbles and through the flanged end of the brake drum, this having a head 73 at one end, the opposite end has a cam lever 74

connected thereto by the pivot pin 14. The head 75 of the lever is cam shaped. The brake band is normally maintained in its open position by a spreading compression spring 76 coiled on the bolt 72 and thrusting outwardly on the flanged ends 67 and 68. When the lever is in the full line position of Fig. 1 the brake is unlocked, the flanged ends being sprung apart and giving a clearance around the pedestal, however when the lever 73 is swung upwardly it brings the cam edge into a thrust action with the thimble 11 thus causing a compression of the spring 76 by a pressing together movement of the flanged ends 67 and 68 of the brake band 66 causing this to clamp on the lower part of the pedestal and thereby hold the column from rotation. The column may be thus held stationary whether or no the worm 51 and worm wheel 18 are in engagement or not.

The hoisting and tilting mechanism for the gun and the gun carriage designated by the assembly numeral 80 includes a vertical guide channel 81 in the column and this is illustrated as opposite the side having the opening for the journal block 45 and the worm 51. This channel is illustrated square in cross section having the side walls 82 and 83 and the end wall 84. Operating in this guide channel 81 there is the vertical hollow rack 85. This is also square in cross section and has rack teeth 86 on its outer face which mesh with a pinion 37. This is mounted on a pinion shaft 83, note Fig. 3, mounted and journaled in a gear case 89, the gear case being molded in the outer wall 84 of the guide channel. This rack has an eye 90 at the top for a purpose hereunder described.

The drive assembly 95 for the pinion 87 and for its shaft 88 includes a sprocket gear 96 on the shaft 88 outside of the gear housing 89. This is actuated by a sprocket chain 97 illustrated as confined within the chain and gear housing 96, note Fig. 1. The driving sprocket 99, note Fig. 6, is mounted on a tubular shaft 100 which is journaled in a long journal boss 101 formed integral with and extending laterally from the column 25 and on the side opposite the channel 81. This shaft has a hand wheel 102 mounted on its opposite end. There are tensioning idlers 103 to maintain the sprocket chain at the proper tension, these being not illustrated in detail. It will therefore be seen that by rotation of the hand wheel 102 the hollow shaft 100 is rotated, hence the driving sprocket 99, the sprocket chain 97, thence the driven sprocket 96 and the shaft 88 with its pinion 87 thus causing an up and down movement of the rack bar 85.

The locking brake 110 for the lifting and lowering assembly, note particularly Fig. 6, includes a friction brake strap 111 which has its inner end 112 secured to one side of the journal boss 101. This has a friction end portion 113 bearing against the end of the hollow shaft 100 opposite the hand wheel 102. A brake applying and releasing rod 114 extends through the hollow shaft 100 through the end 113 and has a washer nut and lock nut assembly 115, the washer bearing against the end 113. A rocking cam 116 is pivoted at 117 to the rod 114. A pull link 118 is pivoted at 119 to this rocking cam. The opposite end of the link is pivoted at 120 to an arm 121 projecting from a handle 122. This handle is pivoted at 123 to the rim of the hand wheel 102. This rim designated 124 is illustrated as circular in cross section, a portion of the handle 122 having an inside surface 125 which is also

10 circular so that the handle fits snugly on the rim of the hand wheel. This handle then when the brake is in the off position may be utilized for rotating the wheel 102. When the rack 85 is raised or lowered to the desired position the handle 122 is then pulled inwardly, that is, towards the axis of the wheel, turning on the pivot 123 and exerting a tension on the link 118 which causes a rocking of the cam 116 developing a cam pressure against one end of the hollow shaft 110 and exerting a tension or pull on the brake applying rod 114 and hence a friction pressure of the end 113 of the friction strip 111 against the end of the shaft 100. This is sufficient to hold the rack 85 with the weight supported thereon at any elevation at which the brake may be applied. Manifestly the brake may be quickly released by bringing the handle 122 to the full line position of Fig. 6 and using this or the rim 124 to rotate the hand wheel and hence the shaft 100.

20 A gun supporting carriage 130, note particularly Figs. 1 and 3, includes a supporting block 131 which has a pair of ears 132 depending therefrom with a pivot pin 133 extending through said ears and through the eye 90 on the upper end of the rack bar 85. An arm 134 extends laterally from the ears and has a cam shaped extension 135 with an elongated curved slot 136 there-through. Through this slot extends a fixed guide pin 137 which is mounted on a stud 138 extending upwardly from the top or cap 28 of the hollow column 25, thus as the rack bar 85 is raised and lowered elevating or lowering the carriage 130 which is pivoted by the pivot 133, there is a tilting and a rocking action of the carriage caused by the guide pin 137 operating in the curved cam slot 136. The end of the slot limits the tilt and hence practically the high angle position of the gun. The carriage has a circular center hub 140 terminating at the bottom in a shoulder 141 and on this is fitted a double yoke 145, this yoke having a hub or central section 146 and is held in place by a cover cap 147 threaded into a recess 148 in the hub 140 of the carriage and locked as to rotation by a hand operated set screw 149. This yoke has double forward arms 150 curved upwardly and double rear arms 151 which extend rearwardly. These double arms each terminate, one in an eye 152, note Fig. 8, having an annular recess and the other in a circular eye 153. Between these eyes is fitted a sleeve 154 having a reduced end 155 fitting in the eye 153 and having a head end 156 fitting in the recessed eye 152. The sleeve has aligned openings 157 through which extends an elevating rod 160, note Figs. 1, 3 and 8. For purposes of clamping this lifting rod there is an inner block 161 slidable in the sleeve 154 and also having an opening 162 through which the rod 160 extends. A reduced threaded stud 163 projects from the block 161 beyond the open end of the sleeve 154 and beyond the eye 153 and on this end there is threaded a hand operated nut 164 having the finger grip spokes 165. By this construction as there is a slight yield of the two yoke ends 151 when the nut 164 is tightened on the stud 163, it gives a reaction of a pull on the block 161 and a relative thrust on the sleeve 154, thus clamping the rod 160 which passes through the openings in the block and the sleeve at such openings. This rod 160 has a finger grip operating head 166 at the bottom and an eye 167 at the top for purposes hereunder detailed.

25 30 35 40 45 50 55 60 65 70 75 The opposite end 158 of the yoke is connected

to the machine gun assembly designated 175, note Figs. 2 and 3 by providing thumb screws 176 which engage through each of the arms of the yoke end 150 and these passing through ears 177 on the machine gun case designated 178. In the particular type of machine gun illustrated the pistol hand grip is designated 179, the cooling tank 180, the muzzle of the barrel 181 projecting, the sights include the front sight 182 and the assembly of rear sights 183. It is manifest however that the machine gun design may vary considerably. The rear end of the machine gun case is connected to the elevating rod 160 by means of the pin 184 engaging in the eye 167 of the rod and being pivoted in downwardly projecting ears 185.

The raising and lowering seat assembly designated 190 includes a quadrilateral system of linkages 191, this having an upper link 192, note particularly Figs. 1 and 3, this being connected by a rock shaft 193 journaled in an elongated boss 194. A lower link 195 is pivoted to the column by a pintle 196, this also being mounted in a substantial journal boss. An end link 197 connects the upper and lower links 192 and 195 by a pintle 198 and 199. An arm 200 is mounted on one end of the rock shaft 193 and is positioned to have a movement at one side of the column 25 and to the lower end of this arm there is connected an operating link 201 by means of the connecting pintle 202, this link extending along the side of the column 25 and being operated as hereunder detailed.

An additional system of linkage 205, note Fig. 1, employs an upper link 206 mounted on the pintle 198. A short inclined arm 207 with a bottom link 208 is connected to the short arm by the pintle 209. A post 210 connects to the bottom link 208 by a pintle 211 and to the upper link 206 by a pintle 212. The post has a head plate 213 at the top and to this is attached the seat 215. This seat is illustrated as having a curved seat bottom 216 and is preferably made of metal, the sides and the front of the seat being provided with a curled rim 217. Manifestly any suitable type of seat may be mounted on the post 210. The seat back 220 has a spring strap 221 which is attached to the seat at the back and the bottom and also preferably to the head plate 213. The upper end of the spring has a backrest 222. It is of course apparent that these may be padded where desired.

The operating equipment to raise and lower and automatically tilt the seat and seat back through the medium of operating the link 211 is by the seat operating assembly designated by the assembly numeral 230, note particularly Figs. 1, 2, 3 and 6. This employs a pinion 231, Fig. 6, attached to the hollow shaft 100 adjacent the hand wheel 102. This meshes with a pivoted quadrant gear 232 which has a set of quadrant teeth 233 and a protecting band 234 spaced from the teeth, thus leaving an open space 235 to accommodate the gear 231. For sake of lightness the quadrant gear is preferably made with two spokes 236 and 237 at its opposite ends and at the hub portion 238 is connected to a substantial rock shaft 240. This rock shaft is journaled in brackets 241, note Figs. 1 and 2 which extend outwardly from the column 25, the rock shaft being slightly spaced from the end wall 34 of the vertical channel 31. Attached to the rock shaft there is an operating radial arm 242 which is connected to the link 201 by a pivot 243.

By this construction it will be seen that when

the main operating wheel 102 is rotated either by the machine gunner or an assistant engaging the rim 124 by his hand or grasping the handle 122, the gear 231 is rotated. This produces an oscillating movement either up or down of the quadrant gear 232, the teeth of the pinion end of the quadrant always meshing and as the protecting band 234 is always outside of the gear 231, there is no danger of the operator or his clothing or anything becoming caught between the gears. This rocking movement of the quadrant of course gives a rocking movement of the rock shaft 240 and hence of the arm 242, therefore developing a longitudinal and substantially reciprocating movement of the link 201. This link through the medium of the arm 200 which is attached to the rock shaft 193 gives an up and down pivoting movement to the upper link 192 and a similar movement is communicated to the lower link 195 by the end link 197. Due to the arcuate and oscillating movement of the upper link 192 manifestly the short arm 207 of the secondary system of linkage 205 also operates and develops a tilting movement of the links 206, 208 and the post 210. This action causes a positive tilt of the post 210, the post being shown in the vertical position of Fig. 1 in which instance the seat may be considered as horizontal. This tilt may incline the post 210 to tilt the seat slightly forward when a machine gun is pointing downwardly and to tilt the seat decidedly backwardly when the machine gun is aiming at a high elevation for high angle fire.

As above mentioned the movement of the machine gun is operated by the same main shaft 100 and through the medium of the sprocket gear 99, the sprocket chain assembly 95 and the gear sprocket wheel 98 which actuates the pinion 97, the rack bar 95 is worked up and down causing a traversal of the arm 134 and its cam shaped end 135 in relation to the fixed guide pin 137, hence as the machine gun is tilted through the medium of tilting the yoke assembly 145 the seat and seat back are simultaneously tilted.

The foot rest assembly 250, note particularly Figs. 1, 2 and 3, includes a short arm 251 which is connected to the rock shaft 240, this being mounted between the brackets 241 and preferably substantially centered in alignment with the vertical guide channel 31. A link 252 is connected by a pintle 253 to the arm 251 and at its lower end operates a bell crank 254, this bell crank having the elbow 255 mounted on a pivot 256 mounted in a bracket 257 extending from the rear wall 34 of the channel 31, the upper arm 258 of the bell crank being connected to the bottom end of the link 252 by the pivot 259. The lower arm of the bell crank 260 has a curved straddle bar 261 rigidly connected thereto, this preferably being diverted rearwardly at a slight inclination towards the seat as illustrated in Figs. 1 and 3. A pair of stirrups or foot rests 262 extend laterally from the ends of this straddle bar. It will be seen therefore that the straddle bar 261 and the stirrups thus straddle the conical shaped foot 12 which supports the pedestal. Therefore the machine gunner when sitting in the seat may comfortably rest his feet on the stirrups, the operator's feet thus straddling the pedestal and this foot rest being released in a convenient position no matter the tilt given to the seat and seat back and the machine gun. It is obvious that as the rock shaft 240 rotates this being actuated by the main hand wheel 102 in the manner above designated, that there is an arcuate swing of the short

arm 251, hence a longitudinal movement of the link 252 and a pivoting movement of the bell crank 254 which manifestly causes an arcuate movement of the stirrups 262 and these stirrups move to bring the operator's feet into a comfortable position in reference to his body no matter how low or high the seat is positioned and no matter what the tilt of the seat. Therefore the movement of the seat, the stirrups and the inclination of the machine gun all operate in unison.

Various changes may be made in the details of the construction without departing from the spirit or scope of the invention as defined by the appended claims.

I claim:

1. In a device as described, a supporting structure for a gun, a rod-like structure mounted thereon for vertical movement, a gun carriage pivotally connected to the upper end of the rod-like structure, the gun carriage having means for attaching a gun, a cam arm rigidly attached to the gun carriage and engaging a fixed guide on the supporting structure, means to raise and lower the rod-like structure to thereby raise and lower the gun carriage and simultaneously tilt such carriage in reference to a horizontal plane.

2. In a device as described and claimed in claim 1, a seat operating assembly including links pivotally connected to the supporting structure of a gun with means for attaching a seat thereto, a drive connection from the means for raising and lowering the rod-like structure to the said links to tilt such links and thereby raise and lower the seat and at the same time tilt the seat in accordance with the raising and lowering and tilting movement of the gun carriage and hence the gun.

3. In a device as described, the combination of a base having a cylindrical pedestal extending thereabove with a closed cap at the top of the pedestal, a column having an inside cylinder with a cylindrical contact surface over the cylindrical pedestal, said column having a cover cap spaced above the top of the pedestal, a support for the column on the pedestal including a thrust shaft attached to the cap of the pedestal and extending through and attached to the cap of the column, a thrust sleeve surrounding said shaft and a thrust bearing engaging the end of the sleeve whereby the sleeve and hence the column may rotate relative to the pedestal and the said thrust shaft and means for mounting a gun operatively connected to the said column.

4. In a device as described, a pedestal having a main column, a vertical guide on the column, a vertical rack guided therein, a gun carriage having a pivotal connection to the rack, an arm rigidly connected to the carriage and having a cam extension, a cam guide secured to the column and means mounted on the column for raising and lowering the said rack and thereby changing the inclination of the gun carriage.

5. In a device as described, the combination of a vertical pedestal cylindrical on the outside, a main column fitted thereover and having an internal bearing therewith, means forming a rotation and thrust bearing between the column and the pedestal, a bar mounted for vertical guided movement on the column, a gun carriage pivoted to the upper end of the bar, a cam means interconnecting the gun carriage and the column to tilt the gun carriage on the lifting and lowering of the bar and a main shaft

rotatably mounted on the main column, means to rotate said shaft and a driving connection between the shaft and means to raise and lower said bar, a system of parallel motion links having a pivotal connection to the column, a secondary system of angular motion links pivotally connected to said first system and having a seat mounted thereon and an actuating connection from the said main shaft to operate the first system of links during the rotation of the shaft and hence the raising, tilting and lowering of the seat as the gun carriage is tilted.

6. In a device as described, the combination of a vertical pedestal cylindrical on the outside, a main column fitted thereover and having an internal bearing therewith, means forming a rotation and thrust bearing between the column and the pedestal, a bar mounted for vertical guided movement on the column, a gun carriage pivoted to the upper end of the bar, a cam means interconnecting the gun carriage and the column to tilt the gun carriage on the lifting and lowering of the bar and a main shaft rotatably mounted on the main column, means to rotate said shaft and a driving connection between the shaft and means to raise and lower said bar, a system of parallel motion links having a pivotal connection to the column, a secondary system of angular motion links pivotally connected to said first system and having a seat mounted thereon and an actuating connection from the said main shaft to operate the first system of links during the rotation of the shaft and hence the raising, lowering and tilting of the seat as the gun carriage is tilted, a foot rest assembly having a lever pivoted to the column and having foot rests mounted on a yoke whereby the gunner in sitting on the seat straddles the pedestal with his feet engaging the foot rests and a link connection to the means for operating the first set of links to simultaneously pivot the foot rest in conjunction with the movement of the seat.

7. In a device as described, a main column, a first system of parallel motion links having one portion thereof pivotally connected to the column, a second set of angular motion links pivoted to the first set of links and a seat mounted on the second set, means mounted on the column to move the first set of links and a pivot connection between one of the links of the first set and one of the links of the second set to give the second set an angular motion while the first set of links have a parallel motion to raise, lower and tilt the seat, a foot rest assembly having a yoke with foot rests with a pivotal connection to the main column, an actuating connection between the means to move the first set of links and the yoke to swing the yoke on its pivot whereby the foot rests on the yoke move toward a position in front of the seat and below the same when the seat is raised and recede from the seat when the seat is lowered.

8. In a device as described, the combination of a supporting structure, a raising and lowering device mounted thereon, a gun carriage having a pivotal connection to the raising and lowering device, such carriage being adapted for mounting a gun, means interconnecting the gun carriage and the supporting structure to change the inclination of the carriage as to the horizontal as it is raised and lowered, a seat, a series of interconnected links with pivotal connections between the supporting structure and the seat, a main operating means mounted on the supporting structure, a first driving connection from the

said main operating means to the lifting and lowering device to raise and lower the same and a second driving connection from the said main operating means to raise, lower and tilt the seat whereby as the gun carriage and the gun mounted thereon is depressed below the horizontal, the seat is raised and brought nearer the end of the carriage and when the gun carriage and its gun is elevated to a steep inclination upwardly, the seat is lowered at the same time approaching a vertical line through the pivotal mounting of the gun carriage and the seat is tilted rearwardly.

9. In a device as described, the combination of a supporting structure, a raising and lowering device mounted thereon, a gun carriage having a pivotal connection to the raising and lowering device, such carriage being adapted for mounting a gun, means interconnecting the gun carriage and the supporting structure to change the inclination of the carriage as to the horizontal as it is raised and lowered, a seat, a series of interconnected links with pivotal connections between the supporting structure and the seat, a main operating means mounted on the supporting structure, a first driving connection from the said main operating means to the lifting and lowering device to raise and lower the same and a second driving connection from the said main operating means to raise, lower and tilt the seat whereby as the gun carriage and the gun mounted thereon is depressed below the horizontal, the seat is raised and brought nearer the end of the carriage and when the gun carriage and its gun is elevated to a steep inclination upwardly, the seat is lowered at the same time approaching a vertical line through the pivotal mounting of the gun carriage and the seat is tilted rearwardly, a foot lever having a pivotal connection to the supporting structure and provided with foot rests for the gunner sitting on the seat to engage with his feet and a driving connection from the main operating means to the said foot lever to tilt same on its pivot whereby as the seat is raised the foot rests approach the front of the seat but therebelow and when the seat is lowered and tilted backwardly, the foot rests recede forwardly from the seat.

10. In a device as described, the combination of a central supporting structure adapted for mounting of a gun thereon, a seat mounting including a first set of links with a pair of upper and lower parallel links pivotally connected to said central structure and a third link connected to the first and second links and parallel to the axis of the central structure, a second set of angular motion links having a pivotal connection to the first set of links and an operating connection with said first set, a seat mounted on the second set, a foot support assembly including an arm pivotally connected to the central structure and having foot rests whereby a gunner sitting on the seat may rest his feet on such foot rests, a main shaft with an operating means readily accessible to the gunner, a quadrant gear having a driving connection with such shaft, a first operating connection between the quadrant gear and the first parallel motion links and a second operating connection between the pivoted arm and the foot rests and the said quadrant gear whereby on operation of said shaft and when the seat is raised for a downward firing of a gun, the foot rests approach the front of the seat but below the same and when the seat is lowered and

tilted for directing fire upwardly the foot rests recede forwardly from the front of the seat.

11. In a device as described, the combination of a base having a pedestal, a column rotatably mounted thereon, a gun carriage operatively supported on the column, such carriage having means for mounting a gun, a gear and worm operatively connected between the column and the pedestal for rotation of the column in reference to the pedestal, the worm being journaled in a pivoted journal block, means to rotate the worm, a locking means for the block whereby the said journal block may be locked with the worm and gear in mesh or in the second position in the plane of the gear with the worm out of mesh with the gear, the gun carriage being attached to a rod-like structure vertically slidabie in the column, a cam arm rigidly connected to the carriage and engaging a fixed guide on the column and means operatively connected to the column to raise and lower the rod-like structure and hence raise and lower and simultaneously tilt the gun carriage with the gun mounted thereon.

12. In a device as described, the combination of a vertical pedestal having an outside cylindrical surface, a main column fitted thereover, means forming a rotation and thrust bearing between the column and the pedestal, a bar mounted for vertical guide movement on the column, a gun carriage pivoted to the upper end of the bar, an arm rigidly connected to the carriage and having a cam extension, a cam guide secured to the column and means mounted on the column for raising and lowering the bar and thereby changing the inclination of the gun carriage.

13. In a device as described having a support combined with a seat assembly including a quadrilateral system of linkages with parallel upper and lower links pivoted to the support by pivots a fixed distance apart, a final link pivotally connected by outer pivots to the upper and lower links and of the same length between its pivots as the distance between the pivots of the upper and lower links to the support, an angular set of motion links having a first link pivoted to one of said outer pivots, a second link pivoted to one of the parallel links, a post pivotally connected to the first and the second links, a seat mounted on the post and means connected to the quadrilateral link system to swing the upper, lower and final links in an arc and thereby raise, lower and tilt the angular motion set of links and the seat.

14. In a device as described having a support combined with a seat assembly including a quadrilateral system of linkages with parallel upper and lower links pivoted to the support by pivots a fixed distance apart, a final link pivotally connected by outer pivots to the upper and lower links and of the same length between its pivots as the distance between the pivots of the upper and lower links to the support, an angular set of motion links having a first link pivoted to one of said outer pivots, a second link pivoted to one of the parallel links, a post pivotally connected to the first and the second links, a seat mounted on the post and means connected to the quadrilateral link system to swing the upper, lower and final links in an arc and thereby raise, lower and tilt the angular motion set of links and the seat, a foot rest pivotally connected to the support, a lever and linkage connection between the foot rest and the quadrilateral link system to shift the foot rest in synchronism with the seat to approach the underside of the seat as the seat

raises and to recede forward from the seat as the seat lowers.

15. In a device as described the combination of a support having a rotatable shaft mounted thereon with means to rotate such shaft, a seat assembly including a pair of links pivoted to the said support, a third link pivoted by outer pivots to the pair of links, a second assembly of links including a fourth link connected to one of the outer pivots, a fifth link pivoted to one of the pair of links, a post pivoted to the outer ends of the fourth and fifth links, a seat mounted on the post, a connecting link and rocker arm assembly between the said shaft and the pair of links to move the pair of links in an arcuate path on rotation of the shaft and hence raise, lower and tilt the seat.

16. In a device as described the combination of a support having a rotatable shaft mounted thereon with means to rotate such shaft, a seat assembly including a pair of links pivoted to the said support, a third link pivoted by outer pivots to the pair of links, a second assembly of links including a fourth link connected to one of the outer pivots, a fifth link pivoted to one of the pair of links, a post pivoted to the outer ends of the fourth and fifth links, a seat mounted on the post, a connecting link and rocker arm assembly between the said shaft and the pair of links to move the pair of links in an arcuate path on rotation of the shaft and hence raise, lower and tilt the seat, a foot rest having a bell crank pivoted to the support, a crank connected to the said shaft and a link between said latter crank and the bell crank to move the foot rest upward and towards the seat as the seat raises and downward and from the seat as the seat lowers.

17. In a device as described, a column, a first system of links having a pivotal connection to the column for a movement in a vertical arc, a second set of angular motion links pivotally connected to the first set of links, a seat mounted on the column to move the first set of links in an arcuate motion, a pivotal connection between one of the links of the first set and one of the links of the second set to give the second set a different angular motion when the first set of links move in a vertical arc to thereby raise, lower and tilt the seat, a foot rest assembly having a yoke with a foot rest with a pivotal connection to the column, an actuating connection between the means to move the first set of links and the yoke to swing the yoke on its pivot whereby the foot rests on the yoke move toward a position in front of the seat and below the same when the seat is raised and recedes forwardly from the seat when the seat is lowered.

18. In a device as described, a column, a system of links having their inner ends pivotally connected to the column and a seat mounted on the outer end of the system, means to move the links in a vertical plane, the system of links being connected to raise, lower and tilt the seat, a foot rest assembly having an arm pivoted to the column with foot rests thereon, an actuating connection between the means to move said system of links and the arm to swing the arm in its pivot whereby the foot rest on the arm moves toward a position in front of and below the seat when the seat is raised and recedes forwardly from the seat when the seat is lowered.

19. In a device as described, a support, a rod mounted thereon for vertical movement, a gun carriage pivotally connected to the upper end of

the rod, a cam arm rigidly connected to the gun carriage, a fixed cam guide on the support engaged by the cam arm, a first system of links having a pivotal connection to the support for a movement in a vertical arc, a second set of angular motion links pivotally connected to the first set of links, a seat mounted on the second set of links, a foot rest having an arm pivoted to the support, a rotatable shaft on the support, a first operating means actuated by the shaft to raise and lower the said rod, a second operating connection from the shaft to move the set of links in arcuate motion and thereby raise, lower and tilt the seat, a third operating connection from the shaft to the foot rest arm to oscillate such foot rest on its pivot whereby as the seat raises the foot rest moves towards a position in front of and below the seat and recedes forwardly when the seat is lowered and with the simultaneous movement of the seat the gun carriage tilts, the carriage being adapted for mounting a gun with the rear end always maintained approximately the same distance from the seat.

20. In a device as described, a support, a shaft rotatably mounted therein, a driving connection from the shaft, a hand wheel connected to the shaft and having a rim for rotation of the shaft, a handle pivotally connected to the rim, a link pivotally connected to the handle, a brake applying and releasing mechanism connected to the link and the shaft, the handle being pivoted to the rim to occupy a position in a plane transverse to the shaft with the brake on or a position parallel to the shaft with the brake off.

21. In a device as described, a support, a shaft rotatably mounted therein, a driving connection from the shaft, a hand wheel connected to the shaft, a handle pivotally connected to the rim, a link pivotally connected to the handle, a brake applying and releasing mechanism connected to the link and the shaft, the handle being pivoted to the rim to occupy a position in a plane transverse to the shaft with the brake on or a position parallel to the shaft with the brake off, the brake mechanism including a rod slidably lengthwise in the shaft, a cam pivotally connected to the rod and to the link and contacting one end of the shaft, the rod having a friction brake device operatively connected thereto and to the support to develop a brake action on the end of the shaft opposite that having the hand wheel.

22. A device as described, the combination of a pedestal, a column rotatably mounted thereon and adapted for reception of a gun carriage, a gear on the pedestal, a rotational drive for the column including the column having an open sided journal block pivoted thereto on a pivot parallel to the axis of the column, a hollow shaft journaled in the journal block at its opposite end, a worm on the shaft in the open side of the journal block to engage with the gear, a hand wheel connected to the shaft for rotation of the same, the column having a locking plate with a bolt hole, a bolt slidably mounted in the hollow shaft and having a stem extending through the shaft with a head located adjacent the hand wheel, a spring reacting against the shaft and the bolt to latch the bolt in the bolt hole for a driving connection, the locking plate having a second means to engage the bolt and to retain the journal block and the worm out of driving relation to the gear.

JOHN W. POYSA.
